SUPPORT FOR TUBE FRAMES IN
AXMINSTER LOOMSWilliam W. Robertson, Worcester, Mass., assignor
to Crompton & Knowles Loom Works, Worcester,
Mass., a corporation of Massachusetts

Application January 31, 1935, Serial No. 4,360

12 Claims. (Cl. 139—9)

This invention relates to improvements in supports for the tube frames used in Axminster looms and it is the general object of the invention to provide a support which will brace the tube frame against rearward and downward bending during the wiping-in and pulling-off operations of the tube frame.

In Axminster looms the tuft yarns are drawn from a series of tube frames which are transported by a pair of parallel chains. As each tube frame is presented to transfer position it is disconnected from the chains by transferer arms which move it toward the fabric, dip the tuft yarns through the binder and stuffer warps, roll the tube frame to wipe the tuft yarns into position, and then lift the frames so that the tuft yarns can be cut from the tube frames to form a row of tufts. In wide looms of this type the central portion of the tube frame is likely to bend rearwardly during the wiping-in operation and to sag under its own weight during the pulling-off operation which immediately precedes cutting. It is an important object of my present invention to provide one or more arms or fingers which are so constructed as to move with the transferer arm and engage the tube frame so that the central portions thereof are held in substantial alignment with the ends which are held by the clutches.

Center supports as heretofore constructed have usually been operated by a cam which is independent of the cam or other mechanism which manipulates the transferer arms, and it is a matter of practical difficulty to cause the cams to give the central part and the ends of the tube frame the same character of motion throughout the time that the tube frame is taking part in a tuft forming operation. It is a further object of my present invention to provide center or intermediate braces which shall be locked to the cross shaft which supports the transferer arms, thereby requiring all parts of the tube frame to have the same kind of motions and keep the tube frame substantially straight throughout its tuft forming operation. By this construction I eliminate the cams heretofore used for the intermediate supports and thereby avoid the necessity for the close setting of these cams which has heretofore been necessary. As a result of this construction the control of the tube frame is considerably simplified since the transferer cam mechanism moves not only the transferer arms but also the intermediate braces.

It is a further object of my present invention to accomplish the aforesaid locking when the

transferer arms move downwardly. It is a further object of my present invention to control the motion of the center support so that it moves downwardly relatively to the path traversed by the tube frames as they move with their chains. I have found that the shape of the center brace, which is determined largely by adjacent mechanism, would be likely to interfere with tube frame motions unless some provision were made to move the brace out of interfering position.

With these and other objects in view which will appear as the description proceeds, my invention resides in the combination and arrangement of parts hereinafter described and set forth in the claims.

In the accompanying drawings, wherein a convenient embodiment of my invention is set forth,

Fig. 1 is an end elevation of a loom having my invention applied thereto.

Figs. 2 and 3 are transverse sections through parts of the structure shown in Fig. 1 on an enlarged scale and showing the brace and associated parts in different positions.

Fig. 4 is a front elevation on an enlarged scale taken in the direction of arrow 4, Fig. 2, parts being removed, and

Figs. 5 and 6 are vertical sections on lines 5—5 and 6—6 of Fig. 4, respectively.

Referring more particularly to Fig. 1, I have shown an Axminster loom frame 10 having a bottom shaft 11 which carries the usual cams for operating the several mechanisms of the loom. Among these mechanisms is that for pulling over the tube frames successively to present them one at a time to transfer position. The pull-over shaft 12 is mounted on the bearing brackets 13 secured to the upper part of the loom frame and carries chain sprockets 14 for the transporting chains C, one of which is shown in Fig. 1. A pair of feeding arms 15 and 16 are actuated by a lever 17 deriving its force from the bottom shaft. By means of mechanism not shown but set forth more particularly in Ryon Patent No. 1,553,558 the rocking of the arms 15 and 16 may be caused to turn the sprocket 14 in either direction to cause the chain to travel first in one direction and then in the other, with the tube frame and its tuft yarns traversing a path designated at A, Fig. 1.

The chain is provided with a series of tube frames T one of which is shown in Fig. 1. Each end of each tube frame has an ear or hanger 18 which is attached to a cross bar 19 which in approved constructions is tubular in cross section. The tube frame itself forms no part of my pres-

ent invention and may be of the usual construction, such as shown in Patent No. 1,515,022.

The loom has transferrer arms 20 each of which is provided with clutches 21 which serve to engage the ears 18 for the purpose of disconnecting a tube frame from the transporting chains. The arms 20 are secured to levers 22 which move about substantially vertical axes 23 carried by supports 24 mounted on the transfer shaft 25, shown more particularly in section in Figs. 2 and 3. The shaft 25 may be rocked in the usual manner by a force controlled through rod 26. The apparatus for moving the shaft 25 of itself forms no part of my present invention and may be of the usual construction as in Skinner Patent No. 233,290.

Referring again to Fig. 1, front and back knives 30 and 31, respectively, may be of the usual construction and the lay L carries a reed R which beats up the weft which is laid between the warp threads W. A comb 32 may be located immediately behind the cloth board 33 and caused to rise periodically by well-known mechanism indicated in Fig. 1.

The matter thus far described operates in the usual manner, the chain C presenting the tube frames one at a time to the transfer position indicated in Fig. 1 and the transferrer arms moving first to unclutch a tube frame from the chains and then moving it down to cloth forming position, where the yarn tubes 34 are projected through the warp threads in the formation of pile tufts. The tube frame is then raised while the tufts are held in position and the knives cut the tuft in the tube frame, after which the latter are returned to the chain.

As already indicated it is an important object of my present invention to provide a brace for the intermediate portion of the tube frame which will serve to prevent the latter not only from sagging under the action of gravity but also from bending rearwardly because of frictional contact between the tuft tubes and any of the structure including the binder threads which they may contact in the wiping-in operation. It is to be understood that while I have shown a form of comb at 32 in Fig. 1, yet I am not limited to a loom equipped with such mechanism and my invention is equally applicable with such structures as are shown in patent to Dacey and Robertson No. 1,958,192 which employ guide plates between which the tuft tubes pass. In the latter patent the rearward bending of the tube frame is more pronounced than is the case with the usual Axminster loom employing a comb, but there is a certain amount of rearward bending of the tube frame in all types of Axminster looms.

In carrying my invention into effect I may provide several intermediate braces, but I have shown herein but one. A carrier bracket 40 is secured to the shaft 25 as by a bolt or screw 41, and carries an upper stud 42 on which is pivoted a lever 43 having a rearwardly extending arm 44 with a counter-weight 45. The forward part of lever 43 terminates in an upstanding plate 46 to which is secured a center brace 47 for relative vertical adjustment, as by bolts 48. This brace 47 is given the contour indicated in the drawings largely for the purpose of avoiding interference with certain parts of the loom indicated in Fig. 1 and terminates in a lower forward concave bracing surface 49 which is movable to a position in contact with the bar 19 and concentric with the stud 39 on the transfer arm around which the frame rocks during the wiping-in and pulling-off operations.

The upper surface of the lever 43 is provided with a cam or inclined face 50 which extends upwardly and forwardly and is held by the counter-weight 45 against a roll 51 on a bracket 52 secured to the loom structure between the transfer arms. The arm 43 also has a laterally projecting locking lug 53 for a purpose to be described, see Fig. 4.

The support 40 carries also a lower stud 60 to which is pivoted a lock lever 61, see Fig. 5, having a depending finger 62 to which is attached a spring 63 connected to an eye bolt 64 tapped into the shaft 25. The purpose of the spring 63 is to move the lock lever toward lug 53. The upper end of this lever has a locking jaw 65 the upper limit of which may be determined by an adjusting screw 66 and the lower part of which may be defined by a shelf 67. A roll 68 on stud 69 carried by the lock lever is positioned for coaction with a cam 70 carried by plate 71 bolted to fixed structure such as a part of the bracket 52. The outline of the cam is set forth in Fig. 6, where it will be seen that the upper part thereof inclines downwardly and forwardly as at 72 and then extends forwardly at a sharper angle as at 73 to define a relatively quick drop.

At the beginning of a dipping movement of the tube frame the parts will be in the full line position shown in Fig. 2 with the transferrer arms in their high position and the shaft 25 therefore turned to its extreme right position. Center 42 is therefore at its extreme distance from roll 51 and the cam face 50 is depressed so that the brace 47 lies below the line A, Fig. 1, or as in full lines in Fig. 2. Furthermore, stud 60 is in its highest position and roll 68 is in its extreme right position to hold the locking jaw 65 away from lug 53. When the transferrer arms are to be lowered the shaft 25 is rocked in a left hand direction from that viewed in Fig. 2 and there results a movement of stud 42 to the left and a corresponding lowering of stud 60. As the stud 42 moves toward the roll 51 the counterweight 45 becomes effective through coaction with the inclined surface 50 to cause a relative upward movement of the brace, causing the latter ultimately to reach the position indicated in dotted lines in Fig. 2. This is accompanied by an angular movement on the part of lever 43 relatively to the shaft 25 in a clockwise direction and raises the locking lug 53 toward jaw 65. After engagement of the brace with the tube frame, locking can be effected, since the brace is now in the position it should retain relatively to the tube frame during the tuft forming operation.

Relative movement of the brace, lever 43, shaft 25 and arms 20 is temporarily prevented by contact of the brace with the tube frame, and lug 53 is therefore fixed relatively to stud 60. Further down motion of the latter results in additional movement of the roll 68 to the left, Fig. 2, and the locking jaw 65 ultimately moves around lug 53 to lock the transfer arms, shaft 25 and brace. The locking occurs under the conditions existing when the counter-weight 45 is able to overcome the sagging of the tube frame, and this is determined by the position of the weight along arm 44. During the wiping-in and rolling movements of the tube frame the concave surface 49 remains in bracing relation with respect to the tube frame.

Upon return movement of the tube frame the operations occur in the reverse order from that

already described, the roll 68 being moved to the right as the transferer arms rise to take the locking jaw away from the lug 53 and roll 51 moving up the incline 50 to depress the brace and move the same out of the path of arcuate movement of the tube frame next to be in action or just returning to the tube frame, depending upon the direction of rotation of the chain C.

From the foregoing it will be seen that I have provided a center brace for a tube frame which preferably remains in supporting relation with respect to the tube frame during the several movements of the latter incident to the formation of a pile tuft and that means are provided for locking the brace to the tube frame so that the ends and center of the tube frame are maintained in alignment. It will also be seen that the brace is acted upon to move away from the path traversed by the tube frames as they are presented to or taken from transfer position by the transporting chains. Ordinarily the lug 53 will fit snugly in the locking jaw, this condition being maintained by the setting of screw 66. If, however, there should be any slackness or lost motion between the lug and the jaw the counter-weight 45 will act to hold the lug normally against the screw so that the upward stress exerted by the brace on the tube frame will be the same as that which existed when the parts were locked.

Having thus described my invention it will be seen that changes and modifications may be made therein by those skilled in the art without departing from the spirit and scope of the invention and I do not wish to be limited to the details herein disclosed, but what I claim is:

1. In an Axminster loom operating with tube frames extending between and supported by transporting chains, a shaft extending across the loom, a transferer lever moving with each end of the shaft, said levers to move the tube frame from the transporting chains toward the fabric being woven and support said tube frame during its wiping-in movements, an intermediate support for the tube frame pivotally mounted with respect to and supported by the shaft to engage the tube frame at a point between the ends thereof, and means to lock the support with respect to the shaft and transferer arms to cause said support to move angularly with the shaft and arms and support the tube frame during the wiping-in movements thereof, the means to lock requiring the transferring arms and brace to have substantially the same character of motion during the wiping-in movements of the tube frame.

2. In an Axminster loom operating with tube frames extending between and supported by transporting chains, a shaft extending across the loom, a transferer lever supported by each end of the shaft, said levers to move the tube frame from the transporting chains toward the fabric being woven and support said tube frame during its wiping-in movements, an intermediate support for the tube frame to engage the latter at a point between the ends thereof, said support pivotally mounted with respect to the shaft, and means to lock the support with respect to the shaft and transferer arms to cause said support to move angularly with the shaft and arms to support the tube frame during the wiping-in movements thereof, said means rendered effective to lock by downward movement of the transferer arms when the latter move the tube frame downwardly.

3. In an Axminster loom operating with tube frames extending between and supported by

transporting chains, a cross shaft movable during the wiping-in operation of the tube frame from a given angular position and returnable to said angular position upon completion of the wiping-in operation, transferer arms moving with the shaft to move a tube frame from the transporting chains toward the fabric being woven and to support said frame during the wiping-in movements thereof, a brace for the intermediate portion of the tube frame supported by and movable relatively to the shaft and normally below the tube frame when said shaft is in said given position, means effective as the cross shaft moves from said given position to cause the brace to approach and engage the intermediate portion of the tube frame during downward movement of the transferer arms, and means to lock the brace relatively to the shaft to cause said brace and transferer arms to move together during the wiping-in operation of the tube frame, said means to lock effective to unlock the brace and shaft as the latter returns to said given position.

4. In an Axminster loom operating with tube frames extending between and supported by transporting chains, a cross shaft extending across the loom and movable angularly from a given position and returnable to said given position to complete the wiping-in operation of the tube frame, transferer arms moving with the cross shaft to move the tube frame from the transporting chains toward the fabric and support the said tube frame during the wiping-in movements thereof, an intermediate support for the tube frame supported by the cross shaft, means to hold said support spaced from the tube frame when the shaft is in said given position and effective to cause said support to approach and engage the tube frame during movement of the shaft away from said given position, and a lock to hold the support in fixed position relatively to the shaft and transferer arms while in engagement with the tube frame, said lock effective to unlock the support as the shaft returns to its given position, the first named means thereupon effective to move the support in a direction away from the tube frame.

5. In an Axminster loom operating with a series of tube frames movable along a given path to a transfer position, a cross shaft extending across the loom having an angular movement toward and from a given position, transferer arms moving with the shaft to transport the tube frame in transfer position from the chain toward cloth forming position and to support the tube frame during the wiping-in movements of the latter, an intermediate support carried by the shaft, positioning means effective to hold said support normally in a position away from said path and effective to cause movement of said support toward the path and into engagement with an intermediate part of the tube frame as the latter moves toward the cloth, means to thereafter lock the support relatively to the shaft and transferer arms during the wiping-in movements of the tube frame, said positioning means effective upon return movement of the shaft to said given position to move the support away from said path.

6. In an Axminster loom, a tube frame, transfer means to move the tube frame to cloth forming position, an intermediate brace movable toward the tube frame, connections between the transfer means and brace, and means to lock the brace and transfer means to the connections during the time that the tube frame is moved to cloth

forming position and before the tube frame reaches cloth forming position.

7. In an Axminster loom operating with a tube frame, a transfer shaft and tube frame transfer arms therefor, a lever pivotally supported with respect to the shaft, an intermediate tube frame brace carried by the lever, counter-weighting means acting on the lever to cause the latter to turn in a direction to move the brace toward the tube frame, the amount of supporting of said brace relatively to the tube frame depending upon the counter-weighting means, and means to cause the lever and shaft to move as a unit when the tube frame is near cloth forming position and to preserve the supporting force exerted by the counter-weighted means throughout the time that the brace is in supporting relation with respect to the tube frame.

8. In an Axminster loom operating with a tube frame, a transfer shaft and tube frame transfer arms therefor, an intermediate tube frame brace pivotally mounted with respect to and moving with the shaft, a lock member pivotally mounted with respect to and moving with the shaft, means on the lock member defining a locking jaw, an adjustable element to vary the size of the jaw, a part moving with the brace to enter the jaw, and means to cause the jaw and brace to have interlocking relation as the shaft moves angularly to present the tube frame to cloth forming position.

9. In an Axminster loom operating with a tube frame, a transfer shaft and tube frame transfer arms therefor, a support fastened to the shaft intermediate the transfer arms, an intermediate tube frame brace pivotally mounted to the support at one point, a lock for the brace pivotally mounted to the support at another point, and means operative through angular movement of the shaft and support to cause the brace and lock to have interlocking relation with respect to each other and cause the brace to move with the transfer arms when in supporting relation with respect to the tube frame.

10. In an Axminster loom operating with a tube frame, a transfer shaft and tube frame transfer arms therefor, an intermediate brace for the tube frame movably mounted with respect to and moving angularly with the shaft, a lock member movable relatively to and angularly with the shaft, two cooperating means one moving with the brace and one moving with the lock movable into locking relation with respect to each other by angular movement of the shaft to lock the brace to the shaft and in fixed angular position relatively to the transfer arms while said brace is in supporting relation with respect to the tube frame, one of said means being of variable size to be accommodated to the size of the other means.

11. In an Axminster loom operating with a tube frame, a shaft, tube frame support means on the shaft effective by angular movement of the shaft to move the tube frame to cloth forming position, an intermediate brace for the tube frame, a lock for the brace, and means rendered effective by angular movement of the shaft to cause the lock to lock the brace relatively to the shaft when the latter is in supporting relation with respect to the tube frame.

12. In an Axminster loom operating with a tube frame, a transfer shaft and tube frame transfer arms therefor, an intermediate brace for the tube frame, two members movably mounted on and relatively to the shaft, interlocking means carried partly on each member, one member supporting said brace, means dependent upon angular movement of said shaft to move said member and cause the brace supported thereby to move into supporting relation with respect to said tube frame when said shaft moves angularly in one direction, and control means for the other member rendered operative by angular motion of the shaft to move said other member in a direction to cause the interlocking means to lock the two members together when the brace is in supporting relation with respect to the tube frame.

WILLIAM W. ROBERTSON.
